UNITED STATES PATENT OFFICE.

JOHN H. HARTMAN, OF LANCASTER, PENNSYLVANIA, ASSIGNOR TO JOHN H. HARTMAN AND JOSEPH T. BRENEMAN, TRADING AS THE HUBLEY MANUFACTURING CO., OF LANCASTER, PENNSYLVANIA, A COPARTNERSHIP.

TOY PISTOL.

Application filed November 30, 1923. Serial No. 677,710.

To all whom it may concern:

Be it known that I, JOHN H. HARTMAN, a citizen of the United States, residing at Lancaster, in the county of Lancaster and State of Pennsylvania, have invented certain new and useful Improvements in Toy Pistols; and I do hereby declare the following to be a full, clear, and exact description of the invention, such as will enable others skilled in the art to which it appertains to make and use the same.

This invention relates to toy pistols, or as they are commonly known, paper cap pistols, and the primary object of the invention is to provide a paper cap pistol so constructed that it will prevent backfire or flash when the pistol is operated to explode the paper cap and thus prevent injury to the operator which is incident to the operation of paper cap pistols as heretofore ordinarily constructed.

A further object is to provide a paper cap pistol with simple and efficient means for concentrating in the body of the pistol any sparks or flash generated by the explosion of a cap of large size and causing them to pass out at the forward end thereof and thus practically eliminate backfire.

The invention will first be hereinafter more particularly described, with reference to the accompanying drawings, forming a part of this specification, and then pointed out in the claims at the end of the description.

In said drawings Fig. 1 represents in side elevation a paper cap pistol embodying my invention;

Fig. 2 is a plan view of the same;

Fig. 3 is a side elevation of the right hand side portion of the paper cap pistol shown in Figs. 1 and 2, and

Fig. 4 is a front elevation of the same showing the toy pistol grasped in the hand of the operator in firing position.

Fig. 5 is an enlarged detail fragmentary view illustrating the mode of assembling the parts carrying the anvil and its co-acting brace member.

Referring to said drawings, in which the same reference characters are used to denote corresponding parts in different views, the letters A and B denote opposite side portions of the pistol having an imitation car-

tridge chamber at the rear end of the barrel and a handle extending rearwardly and downwardly from said chamber, similar to an ordinary pistol, the two parts being each formed or cast in one piece and secured together by rivets or screws, as shown. The member A is formed or cast integrally with a laterally and inwardly projecting lug or flange *a* and an integral diagonal brace *a'*, thus forming an anvil against which a cap to be exploded may be placed, and the opposed member B is formed or provided with an inwardly projecting lug or flange *b* against which the flange *a* bears when the two parts are in assembled relation, so as to effectually brace and sustain the anvil member in operative position. The front face of the anvil is preferably convex, as shown, and fits against a concave surface of the lug *b*. The body of the pistol is hollow from end to end of the imitation barrel and cartridge chamber, for a purpose hereinafter described, and the handle portions may likewise be hollowed out for lightness. The opposed members of the cartridge chamber portion are formed with co-incident upwardly and rearwardly turned portions *a*² and *b*², respectively, which extend above the anvil, and with rearwardly extending side portions *a*³ and *b*³ which are turned inwardly and terminate a sufficient distance apart to leave an open space at the rear of the anvil, preferably of rectangular form to receive the correspondingly shaped striking face *c* of the hammer C, as in toy pistols of known construction.

A paper cap receiver is thus formed around the anvil in which a paper cap may be inserted and held against the anvil in position to be struck by the striking face of the hammer as it enters between the inturned end portions *a*³ and *b*³ of the receiver, so as to explode the cap placed against the anvil, and by the described construction air spaces or vents are formed above and below the anvil and on each side thereof opening into the hollow body of the pistol, so that any sparks or flash may be expelled through the barrel and subjacent hollow body when the hammer is snapped or closed; the hammer being so constructed as to effectually cover and close the normally open top and side and rear portions of the recess forming the

cap-receiver, thereby forming air spaces or vents completely around the anvil opening into the body of the pistol when the hammer is in closed or operated position, so that 5 flash or sparks due to the explosion of a cap may be freely discharged through the pistol body, the passageway through the same being substantially co-extensive with the hollow interior formation of the barrel 10 and imitation cartridge receiving chamber.

The hammer C is arranged in close proximity to the imitation cartridge chamber and projects upwardly through a slot or recess provided therefor between the handle 15 portions of the two parts A and B, while the trigger portion c^1 thereof projects downwardly through a similar slot in the bottom or lower side of said parts. The hammer has preferably a rectangular striking face 20 and side flanges c^2 adapted to fit against the inturned portions a^2 and b^2 of the cap receiver, and a top flange c^3 projecting forwardly over the striking face, and preferably the outer edges of the rearwardly and 25 upwardly extending portions a^2 and b^2 of the cartridge chamber portion of the pistol are beveled on the upper side thereof while the forward edge of the flange c^3 is reversely beveled to adapt the device to deflect outwardly and away from the operator any sparks or backfire that may possibly escape when the hammer is snapped or closed to 30 explode a cap. The shank of the hammer is formed or provided with a forwardly projecting pivot pin or lug c^4 which rests loosely in the concave rear face of a laterally and rearwardly extending flange a^4 on the inside of the cartridge chamber portion of the member A, and a leaf spring D, has one end 35 fitted in a recess c^5 in the shank of the hammer and the other end abutting against a shoulder a^5 on the inside of the handle portion of the member A, so that when the hammer is swung backwardly into position for 40 operating it to explode a cap the recess c^5 will be below the pivot or fulcrum of the hammer and the pressure of the spring will hold the hammer in firing position. On pulling the trigger to explode the cap the 45 recess c^5 will be positioned above the fulcrum of the hammer and the spring will hold the hammer in operated position, as shown in full lines.

I thus provide a very simple and harmless paper cap pistol, which may be manufactured and sold at a very small price, and may be used by children without danger of injuring them in using caps of large size. This simple device has the advantage over 55 toy pistols as heretofore ordinarily constructed of practically eliminating backfire, by providing for the expulsion of sparks or flash produced by the explosion of a paper cap through the body of the pistol and out 60 at the forward end, instead of trying to pre-

vent the same from passing rearwardly as heretofore proposed, by providing for their expulsion laterally or sidewise.

Having thus described my invention, what I claim as new and desire to secure by Letters Patent of the United States is:

1. A toy pistol having a hollow body and a recess at the rear end thereof forming a cap-receiver, and an anvil arranged within said recess so as to provide air vents above and below the anvil opening into said hollow body.

2. A toy pistol having a hollow body provided at the rear end thereof with a vertically disposed recess forming a cap-holder, said recess being in open communication with the hollow body, and an anvil arranged within said recess so as to provide air vents above and below opening into said hollow body.

3. A toy pistol having a hollow body provided with a cap-receiver at the rear end thereof having inturned portions the ends of which are spaced apart to permit the striking face of a hammer to enter therebetween, an anvil arranged within said receiver and spaced therefrom so as to provide air vents around the anvil opening into the hollow body, and a hammer having a striking face adapted to enter the opening between said inturned portions and laterally projecting side portions, and a forwardly projecting top portion for closing the space around said anvil so as to form air vents above and below and on both sides of the anvil opening into said hollow body.

4. A toy pistol comprising two members together forming a hollow body having a barrel with imitation cartridge chamber and handle and a cap-receiver at the rear end of said chamber provided on one side with inturned portions spaced apart to permit the striking face of the hammer to enter therebetween, an anvil within the receiver, a hammer having a striking face and side and top flanges adapted to close the open space around the anvil and leave air spaces or vents above and below and on opposite sides of the anvil opening directly into the hollow body for discharging through said body sparks or flash caused by the explosion of a paper cap.

5. In a toy pistol having a barrel and imitation cartridge chamber forming a hollow body, a cap-receiving recess at the rear of said chamber open on one side, an anvil spanning said recess, and a hammer having a striking face and side and top flanges for closing the space around the anvil so as to provide air vents above and below and at the sides thereof opening directly into the hollow body for discharging backfire or sparks through said body.

6. A toy pistol having a hollow body provided at the rear end thereof with a verti-

- cally disposed recess of substantially oblong cup-shaped form open on one side to receive the striking face of a hammer and forming a cap-holder, a hammer, and an 5 anvil plate spanning said recess so as to provide an air space extending around the anvil and opening into said hollow body.
7. A toy pistol having a hollow body provided with a vertically disposed recess of 10 substantially oblong cup-shaped form forming a cap-holder at the rear end thereof, an anvil plate spanning said recess, and a hammer having a striking face and laterally projecting side flanges and an integral forwardly projecting top flange for closing the space around said face and the anvil so as to leave air spaces above and below and on both sides of the anvil opening directly into the hollow body.
- 20 8. A toy pistol having a hollow body and a cap-receiver having an open top and open on one side, an anvil in said receiver, a ham- mer having a striking face adapted to enter the open side of said receiver and provided with a forwardly projecting top and laterally projecting side portions whereby the space around the anvil is closed when the hammer is in closed position and air spaces or vents provided extending completely around the anvil and opening into the hollow body for discharging backfire or sparks through said body; the rear edge of the receiver overlying the anvil being beveled and the edge of said forwardly projecting top reversely beveled so as to effectually close the space around the anvil between it and the hammer when the hammer is snapped or closed.
- In testimony whereof I affix my signature in the presence of two witnesses.
- JOHN H. HARTMAN.
